UNITED STATES PATENT OFFICE.

ALFRED H. DYSON, OF CHICAGO, ILLINOIS, ASSIGNOR TO MILO G. KELLOGG, OF CHICAGO, ILLINOIS.

TELEPHONY.

No. 830,654.

Specification of Letters Patent.

Patented Sept. 11, 1906.

Application filed April 3, 1905. Serial No. 253,475.

To all whom it may concern:

Be it known that I, ALFRED H. DYSON, a citizen of the United States, and a resident of Chicago, county of Cook, and State of Illinois, have invented new and useful Improvements in Telephony, (Case C⁸), of which the following is a specification.

My invention relates particularly to telephone systems for furnishing measured service to subscribers.

It is adapted to be employed in connection with automatic telephone systems, and it is in connection with such a system that I have illustrated and described it. In the system shown a calling device is provided at subscribers' stations adapted to transmit currents over the lines, the interconnection of lines at the central office being secured by switching mechanism responsive to these currents. In the said systems apparatus is provided to enable a calling subscriber to ring the bell of a connected called subscriber.

In accordance with my invention the subscriber, whose substation is equipped with a measured service or pay-station device such as I show and describe, is enabled to establish connection between his line and the line of the called subscriber without depositing a coin or token in the device. The coin must, however, be deposited in the pay-station device to enable the subscriber to ring the bell of a connected subscriber. I provide means for collecting the deposited coin upon the response of the called-for subscriber and for returning the coin to the calling subscriber in case the called-for subscriber fails to respond.

The object of my invention is to provide an efficient arrangement of the specified character.

Referring to the drawings, Figures 1, 2, 3, 4, and 5 illustrate five different arrangements of substation apparatus embodying my invention. Fig. 6, consisting of Sheets 1 and 2, illustrates a portion of two telephone-lines terminating at the central office and automatic telephone-exchange switchboard apparatus adapted to operate in connection with the substation arrangements shown in the preceding figures to interconnect the said lines for conversation.

Referring first to Fig. 1, I show substation apparatus consisting of transmitter 1, induction-coil 2, receiver 3, hook-lever 4, with its associated anvils 5 6 and 7 8, condenser 9,

bell 10, and calling device 20. The latter is 55 adapted to be rotated by the subscriber in the direction indicated by the arrow, returning when released to the normal position shown in the illustration, the ratchet-teeth of the device closing and breaking contact 60 between springs 21 and 22 as many times as the subscriber has moved teeth of the ratchet below spring 22. After the last contact between springs 21 and 22 has been made and broken a ratchet-tooth closes and breaks contact between springs 18 and 19 a single time. Springs 22 and 18 are connected, respectively, to limbs P and S of the telephone-line, while springs 21 and 19 are connected to ground 17, the arrangement of the whole providing 70 means enabling the subscriber to establish ground connections to the two limbs of the telephone-line in a predetermined manner for operating the switchboard apparatus illustrated in Fig. 6. Arm 11 is adapted to coöperate with springs 12 13 14 in releasing the central-office apparatus when the subscriber desires to terminate a connection. I also show in Fig. 1 a coin-slide 40, associated switch-springs 34, 35, 36, 37, and 38, a push-button 39, and slots 43 and 44, rendering possible the movement of ends 31 and 30 of arms 32 and 28 toward the middle and away from the middle of coin-slide 40.

The operation of the described pay-station 85 device is as follows: A subscriber desiring to ring another subscriber removes his telephone from the hook, whereupon hook-lever 4 moves upward, breaking engagement with anvils 7 and 8 and engaging anvils 5 and 6. 90 At the same time arm 32 being rigidly attached to hook-lever 4 moves its end 31 toward the middle of coin-slide 40 until it rests in a position toward the inwardly-projecting end of slot 43. The subscriber may 95 do this before he operates the calling device 20 to establish a desired connection or thereafter. Having removed the receiver from its hook, the subscriber deposits a suitable coin in coin-slide 40, which descends by gravity 100 until it rests upon ends 30 and 31 of arms 28 and 32. In this position it presses outwardly buffer 42, thereby causing spring 38 to engage spring 37, thus placing the winding of relay 25 in parallel with the talking-circuit 105 of the substation. Connection having been established with the line of the desired subscriber, the calling subscriber now depresses

2

push-button 39, which engaging one edge of the deposited coin transmits its motion to buffer 42, engaged by the other edge, which in turn transmits the motion to buffer 41, 5 moving circuit-changing-switch spring 35 out of engagement with spring 36 and into engagement with spring 34. This establishes ground to limb P of the telephone - line through contact 34 35 and through contact 10 23 24 and causes the bell of the called-for subscriber to ring as long as the calling subscriber holds push - button 39 depressed. When he releases it, it resumes its normal position, as shown, spring 35 resumes its normal 15 position in engagement with spring 36, disengaging spring 34, springs 37 and 38 maintaining their before - described engagement. When the called-for subscriber responds to the call, he causes a source of current at the central office to be included in the metallic circuit of the telephone-line of the calling subscriber, current therefrom passing through the substation (illustrated in Fig. 1) over the following path: over limb P of the 20 telephone-line, through contact 24 23, through contact between springs 35 and 36, the said current thereupon dividing, a portion flowing through transmitter 1 through contact 6 4, through contact 4 5, through one winding of 25 induction-coil 2, returning over limb S of the telephone - line, another portion flowing through the winding of electromagnet 25, through contact between springs 38 and 37, returning over limb S of the telephone-line. 30 The last-described flow of current energizes electromagnet 25, which thereupon attracts its armature 26. Arm 27 is pivoted to armature 26 and arm 28, which latter arm is pivoted at 29. The aforementioned attraction 35 of armature 26 causes arm 28, turning upon its pivot 29, to move end 30 in slot 44 to the side of coin-slide 40. This movement places end 30 in a position where it no longer acts as a support to the deposited coin, which thereupon descends by gravity through portion 45 of coin-slide 40 into a receptacle provided for collections. In case the called-for subscriber fails to respond to the call the calling subscriber replaces receiver 3 upon the hook, 50 and the resulting movement of hook-lever 4 returns end 31 of arm 32 to its normal position, as shown in Fig. 1, and the said end no longer serves as a support to the deposited coin. The latter descends by gravity through portion 45 of coin-slide 40 and is returned to the 55 subscriber. It will be noted that the calling subscriber retains control, by means of hook-lever 4, of a deposited coin at all times until the called-for subscriber actually responds to 60 the call.

Referring to Fig. 6, consisting of Sheets 1 and 2, I show at A a first selector-switch, which may be considered as connected by lines P and S with the substation illustrated 65 in Fig. 1, including movable switch-arms 47

48, 49, and 50, with which may be associated multiplied terminals of a plurality of second selector-switches, (one of which I have illustrated at B,) which latter switches may be arranged in groups, the switches of each group being adapted when their terminals are engaged by first selector-switches, such as I have illustrated at A, for continuing circuits from telephone-lines connected to the said first selector-switches to certain limited groups of subscribers' lines represented by connector-switches. Included in first-selector-switch A, I have illustrated a suitable organization of circuits and electromagnets adapted in response to switching movements 80 of calling device 20 (illustrated in Fig. 1) to enable the calling subscriber to select the group of second selector-switches appropriate for establishing a desired connection. The circuits and electromagnets shown at A include means responsive to further switching movement of calling device 20 for causing wipers 47, 48, 49, and 50 to move over the terminals of the selected group of second selector-switches, their motion being arrested 85 automatically as soon as they engage terminals of an idle switch. Assuming that the subscriber, whose substation is illustrated in Fig. 1, is making a call, has selected a group of second selector-switches, including switch 90 B, and that wipers 47, 48, 49, and 50 of switch A have been arrested when engaging multiplied terminals 51, 52, 53, and 54 of switch B, the said switch may now be operated under control of calling device 95 20 of Fig. 1. Included in the mechanism of the said second selector-switch are wipers 57, 58, 59, and 60, with which may be associated multiplied terminals of a plurality of connector - switches, one of which I have 100 illustrated at C, which latter switches may be arranged in groups, the switches of each group being adapted, when their terminals are engaged by second selector-switches in operative relation with subscribers' lines, for continuing circuits from such telephone-lines through to a certain limited number of subscribers lines. Included in second selector-switch B, I have illustrated a suitable organization of circuits and electromagnets adapted in response to switching movements 105 of calling device 20 (illustrated in Fig. 1) to enable the calling subscriber to select a group of connector-switches appropriate for establishing connection directly to the line of 110 the desired subscriber. The circuits and electromagnets shown at B include means responsive to further switching movement of calling device 20 for causing wipers 57, 58, 59, and 60 to move over the terminals of the 115 selected group of connector-switches, their motion being arrested automatically as soon as they engage terminals of an idle switch. Assuming this to occur when they engage terminals 61, 62, 63, and 64 of connector-switch 120 125 130

C, the said connector-switch may be operated under control of calling device 20 of Fig. 1. Included in connector-switch C are wipers 78, 79, and 80, with which are associated 5 multiplied terminals of a plurality of subscribers' lines adapted to be engaged by wipers 78, 79, and 80. Included in connector-switch C, I have illustrated a suitable organization of circuits and electromagnets adapted 10 in response to switching movements of calling device 20 (illustrated in Fig. 1) to enable the calling subscriber to cause wipers 78, 79, and 80 of the connector-switch to pick out and engage terminals of any desired subscriber's line in the group of lines whose terminals are associated with connector-switch C. Assuming that the desired subscriber's line is included in said group and is that whose first selector-switch is shown at D, the 15 calling subscriber causes wipers 78, 79, and 80 to be placed in engagement with terminals 181, 182, and 183 of the said line. In case the line of the called subscriber is busy connector-switch C is automatically released and 20 returns to normal, wipers 78, 79, and 80 disengaging the terminals 181, 182, and 183, and the calling subscriber receives the characteristic busy-signal from busy-back machine 85. He thereupon replaces his receiver upon the switch-hook, which in case he has already deposited the coin causes the return of the coin to himself. The above-described act also operates to disconnect second selector-switch E from connector-switch C 25 and first selector-switch A from second selector-switch B. In case the line of the called-for subscriber is idle wipers 78, 79, and 80 rest in engagement with terminals 181, 182, and 183. In this case (referring to 30 Fig. 6) the switching operations completing the connection established a circuit through the switches employed in the connection which may be traced as follows: from limb P of the telephone-line of the calling subscriber 35 through contact between arm 93 and contact-point 94, through contact 49 53, through contact between arm 193 and contact-point 194, through contact 59 63, through condenser 72, through contact between arm 101 50 and contact-point 102, through contact 79 182 over limb P of the called-for subscriber's line, through the substation ringing equipment, over limb S of said line, through contact 183 80, contact between contact-point 55 104 and arm 103, through condenser 73, through contact 64 60, through contact between contact-point 196 and arm 195, through contact 54 50, through contact between contact-point 96 and arm 95, over limb 60 S of the calling-subscriber's line and through the substation to limb P of said line. The calling subscriber in this case rings the bell of the called-for subscriber in the manner already described in connection with Fig. 1, a 65 coin having been deposited in the pay-sta-

tion. When the called-for subscriber responds to the call by removing the receiver from the switch-hook, he closes circuit at the substation between limbs P and S of his telephone-line, establishing a path for the flow of current as follows: from the grounded side of battery 125, through the winding of relay 67, in circuit therewith, through contact 101 102, through contact 79 182, over limb P of the telephone-line, returning over limb S, through 75 contact 183 80, through contact 104 103, through the other winding of relay 67 to the active side of battery 125. This flow of current energizes the said relay and supplies current for talking purposes to the transmitter 80, of the called-for subscriber. The energization of relay 67 attracted armatures 126 and 127, establishing a path for the flow of current as follows: from the grounded side of battery 70, over conductor 68, through armature 126, through contact 63 59, contact 194 193, contact 53 49, through contact 94 93, over limb P of the calling-subscriber's line, through the substation of Fig. 1, causing the deposited coin to be collected in the manner previously described, the current returning over limb S of the said line, through contact between arm 95 and contact-point 96, through contact 50 54, contact between arm 195 and contact-point 196, through contact 60 64, through the winding of electromagnet 66, armature 127, conductor 69, to the active side of battery 70. This flow of current supplies current for talking purposes to the transmitter of the calling subscriber. The 90 subscribers are now in conversation. When they have finished their conversation, they replace their receivers on the hooks. When either subscriber does this, connector-switch C is released, and when the calling subscriber does so the second selector-switch B and first selector-switch A are also released. 100

While I have shown a plurality of batteries in Fig. 6 for convenience of illustration, it is to be understood that they may be one and 105 the same battery.

Referring now to Fig. 2, the arrangement there shown is generally similar to that illustrated in Fig. 1. In the said Fig. 2, however, the winding of electromagnet 25 is normally in parallel with the talking-circuit of the substation. When the coin is deposited in slide 40 preparatory to ringing, its engagement with buffer 42 causes spring 37^a to disengage spring 38^a, thereby placing the winding of electromagnet 25 in series with the talking-circuit of the substation. The bell of the called-subscriber's line is rung in the manner similar to that described in connection with the arrangement of Fig. 1; but upon the response of the called subscriber the current causing the energization of electromagnet 25 to collect the deposited coin passes through the said winding in series with the talking-circuit. The collection of the coin 115 120 125 130

causes spring 37^a to again engage spring 38^a, reestablishing the normal talking-circuit of the substation, the winding of electromagnet 25 being in parallel with the talking-circuit 5 during conversation.

Referring now to Fig. 3, the arrangement there shown is similar to that shown in Fig. 1, with the exception that different means are provided for returning a deposited coin to the subscriber. In the present figure an additional electromagnet 25^a is provided, its armature 26^a operating to move end 31^a of arm 28^a away from its normal position (shown in the illustration) when the electromagnet is energized, accomplishing the return of the deposited coin by withdrawing the said end 31^a out of supporting relation with the said coin. The energization of the said electromagnet is accomplished in the following manner: When the subscriber replaces his receiver on the hook, the portion of hook-lever 4 designated 11 engages spring 14 as it moves upward, causing spring 14 to engage spring 13 and spring 13 to engage spring 12, and as it continues this movement releases spring 14, allowing the said springs to resume their normal positions. This temporary engagement of springs 12 and 13 establishes a path for the flow of current from ground 15 through the winding of electromagnet 25^a, through contact between springs 12 and 13, through contact 23 24, over limb P of the line to battery at the central office, energizing the said electromagnet 25^a.

Referring to Fig. 4, the arrangement there illustrated embodies means similar to those described in connection with Fig. 3 for securing the return of the deposited coin to the subscriber. The circuit arrangement of electromagnet 25 illustrated in the said figure is similar to that of the similarly-designed electromagnet described in connection with Fig. 2.

Referring to Fig. 5, the arrangement there shown provides means similar to those described in connection with Figs. 1 and 2 for securing the return of a deposited coin to the subscriber. In the present figure arm 28 is jointly controlled by electromagnets 25 and 25^b. In the previously-described arrangements the return of arm 28 to its normal position upon the deenergization of electromagnet 25 was secured by gravity. In the present structure this return is secured by the permanent magnetism of polarized electromagnet 25^b. The windings of the two electromagnets are normally in parallel with the talking-circuit of the substation. When a coin is deposited in the slide, the windings 60 of the two electromagnets are placed in series with the talking-circuit by the disengagement of spring 37^d from spring 38^d. When the called-for subscriber, in answering the call, includes current in the metallic circuit of the line of the substation illustrated in

Fig. 5, the current passes through the winding of electromagnet 25, energizing the said electromagnet, and through the winding of electromagnet 25^b in a direction to neutralize the permanent magnetism of the said electromagnet, thereby neutralizing the attractive force normally holding armature 26^b in the position illustrated and enabling electromagnet 25 to freely attract its armature 26 to move arm 28 to collect the deposited coin. As soon as current ceases to flow through electromagnets 25 and 25^b the permanent magnetism of the latter magnet, no longer neutralized, causes the attraction of its armature 26^b to cause the return of arm 28 to its normal position. (Shown in Fig. 5.)

It will be noted in the arrangement shown in Fig. 5 that the current for causing the collection of a deposited coin must be in a direction to neutralize the permanent magnetism of electromagnet 25^b. Should current be caused to flow over the line in a reverse direction, the induced magnetic effect will aid the permanent magnetism of relay 25^b in holding its armature in its attracted normal position, and this combined attractive force will overbalance the attractive force which relay 25 exerts upon its armature 26. Armature 26 under these circumstances remains unmoved, and a deposited coin would therefore not be collected. Other arrangements of polarized electromagnetic apparatus may be employed to secure the above-described method of operation. The interchangeable use of such structures as are illustrated in Figs. 1 to 5 as pay-stations and call-counters is well known.

I claim—

1. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of a deposited coin to operate said switching mechanism, means adapted, in response to the operation of said mechanism, to cause the bell of the called subscriber to ring, and apparatus associated with said device for collecting a deposited coin adapted to be operated by the response of the called subscriber.

2. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a

movement of a deposited coin to operate said switching mechanism, means adapted, in response to the operation of said mechanism, to cause the bell of the called subscriber to ring, apparatus associated with said device for collecting a deposited coin adapted to be operated by the response of the called subscriber, and apparatus associated with said pay-station device and controlled by the calling subscriber adapted to release a deposited coin and destroy the connection prior to the response of the called subscriber.

3. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage a deposited coin and cause movement thereof, a circuit-changing spring associated with said device, mechanical means for transmitting the motion of said coin to said spring, switching apparatus adapted, in response to such motion of said spring, to cause the bell of the called subscriber to ring and apparatus associated with said device for collecting said coin adapted to be operated by the response of the called subscriber.

4. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage a deposited coin and cause movement thereof, a circuit-changing spring associated with said device, mechanical means for transmitting the motion of said coin to said spring, switching apparatus adapted, in response to such motion of said spring, to cause the bell of the called subscriber to ring, apparatus associated with said device for collecting a deposited coin adapted to be operated by the response of the called subscriber, and apparatus associated with said pay-station device and controlled by the calling subscriber adapted to release a deposited coin and destroy the connection prior to the response of the called subscriber.

5. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of a deposited coin to operate said

switching mechanism, means adapted, in response to the operation of said mechanism, to cause the bell of the called subscriber to ring, an electromagnet in circuit with the calling-subscriber's line at the substation adapted to be energized upon the response of the called subscriber and mechanism controlled by said electromagnet adapted, upon its energization, to collect a deposited coin.

6. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of a deposited coin to operate said switching mechanism, means adapted, in response to the operation of said mechanism, to cause the bell of the called subscriber to ring, an electromagnet in circuit with the calling-subscriber's line at the substation adapted to be energized upon the response of the called subscriber, mechanism controlled by said electromagnet adapted, upon its energization, to collect a deposited coin, and apparatus associated with said pay-station device and controlled by the calling subscriber adapted to release a deposited coin and destroy the connection prior to the response of the called subscriber.

7. In an automatic telephone-exchange system, the combination with a calling-subscriber's line and a called subscriber's line switched to electrical connection at the central office, of a pay-station device associated with the line of the calling subscriber at the substation, adapted to receive a deposited coin, a push-button adapted, when depressed by the subscriber, to engage a deposited coin and cause movement thereof, a circuit-changing spring associated with said device, mechanical means for transmitting the motion of said coin to said spring, switching apparatus adapted, in response to such motion of said spring, to cause the bell of the called subscriber to ring, an electromagnet in circuit with the calling-subscriber's line at the substation adapted to be energized upon the response of the called subscriber, and mechanism controlled by said electromagnet adapted, upon its energization, to collect a deposited coin.

8. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and

- 6
- cause movement thereof, a circuit-changing spring associated with said device, mechanical means for transmitting the motion of a deposited coin to said spring, switching apparatus adapted, in response to such motion of said spring, to cause the bell of the called subscriber to ring, an electromagnet in circuit with the calling subscriber's line at the substation adapted to be energized upon the response of the called subscriber, mechanism controlled by said electromagnet adapted, upon its energization, to collect a deposited coin, and apparatus associated with said pay-station device and controlled by the calling subscriber adapted to release a deposited coin and destroy the connection prior to the response of the called subscriber.
11. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, an electromagnet in circuit with the calling-subscriber's line at the substation adapted to be energized upon the response of the called subscriber, mechanism controlled by said electromagnet adapted, upon its energization, to collect a deposited coin, and a relay at the central office associated with the called-subscriber's line adapted to be operated by the response of the called subscriber to energize said electromagnet by causing a flow of current over the calling-subscriber's line.
12. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, an electromagnet in circuit with the calling-subscriber's line at the substation adapted to be energized upon the response of the called subscriber, mechanism controlled by said electromagnet adapted, upon its energization, to collect a deposited coin, a relay at the central office associated with the called-subscriber's line adapted to be operated by the response of the called subscriber to energize said electromagnet by causing a flow of current over the calling-subscriber's line, and apparatus associated with said pay-station device and controlled by the calling subscriber adapted to release a deposited coin.
9. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet in circuit with the calling subscriber's line at the substation adapted to be energized upon the response of the called subscriber, mechanism controlled by said electromagnet adapted, upon its energization, to collect a deposited coin, and a relay at the central office associated with the called-subscriber's line adapted to be operated by the response of the called subscriber to energize said electromagnet by causing a flow of current over the calling-subscriber's line.
10. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet in circuit with the calling-subscriber's line at the substation adapted to be energized upon the response of the called subscriber, mechanism controlled by said electromagnet adapted, upon its energization, to collect a deposited coin, a relay at the central office associated with the called-subscriber's line adapted to be operated by the response of the called subscriber to energize said electromagnet by causing a flow of current over the calling-subscriber's line, and apparatus associated with said pay-station device and controlled by the calling subscriber adapted to release a deposited coin.

ited coin and destroy the connection prior to the response of the called subscriber.

13. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet associated with said device switched into operative relation with the calling-subscriber's line by the deposit of a coin, a relay at the central office associated with the called-subscriber's line adapted to be operated by the response of the called subscriber to energize said electromagnet by causing a flow of current over the calling-subscriber's line, mechanism controlled by said electromagnet adapted, upon its energization, to collect a deposited coin, and a switch adapted to be actuated by the collection of said coin to place said electromagnet in inoperative relation with the telephone-line.

14. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet associated with said device switched into operative relation with the calling-subscriber's line by the deposit of a coin, a relay at the central office associated with the called-subscriber's line adapted to be operated by the response of the called subscriber to energize said electromagnet by causing a flow of current over the calling-subscriber's line, mechanism controlled by said electromagnet adapted, upon its energization, to collect a deposited coin, apparatus associated with said pay-station device and controlled by the calling subscriber adapted to release a deposited coin and destroy the connection prior to the response of the called subscriber, and a switch adapted to be actuated by the collection or release of said coin to place said electromagnet in inoperative relation with the telephone-line.

15. In an automatic telephone-exchange system, the combination with a calling-sub- 65 scriber's line and a called-subscriber's line switched to electrical connection at the central office, of a pay-station device associated with the line of the calling subscriber at the substation, adapted to receive a deposited 70 coin, a push-button adapted, when depressed by the subscriber, to engage said coin and cause movement thereof, a circuit-changing spring associated with said device, mechanical means for transmitting the motion of 75 said coin to said spring, switching apparatus adapted, in response to such motion of said spring, to cause the bell of the called subscriber to ring, an electromagnet associated with said device switched into operative re- 80 lation with the calling-subscriber's line by the deposit of a coin, a relay at the central office associated with the called-subscriber's line adapted to be operated by the response 85 of the called subscriber to energize said electromagnet by causing a flow of current over the calling-subscriber's line, mechanism controlled by said electromagnet adapted, upon its energization, to collect a deposited coin, and a switch adapted to be actuated by the 90 collection of said coin to place said electromagnet in inoperative relation with the telephone-line.

16. In an automatic telephone-exchange system, the combination with a calling-sub- 95 scriber's line and a called-subscriber's line switched to electrical connection at the central office, of a pay-station device associated with the line of the calling subscriber at the substation, adapted to receive a deposited 100 coin, a push-button adapted, when depressed by the subscriber, to engage said coin and cause movement thereof, a circuit-changing spring associated with said device, mechanical means for transmitting the motion of 105 said coin to said spring, switching apparatus adapted, in response to such motion of said spring, to cause the bell of the called subscriber to ring, an electromagnet associated with said device switched into operative re- 110 lation with the calling-subscriber's line by the deposit of a coin, a relay at the central office associated with the called-subscriber's line adapted to be operated by the response 115 of the called subscriber to energize said electromagnet by causing a flow of current over the calling-subscriber's line, mechanism controlled by said electromagnet adapted, upon its energization, to collect a deposited coin, apparatus associated with said pay-station 120 device and controlled by the calling subscriber adapted to release a deposited coin and destroy the connection prior to the response of the called subscriber, and a switch adapted to be actuated by the collection or 125 release of said coin to place said electromag-

net in operative relation with the telephone-line.

17. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, a central source of current, apparatus at the central office adapted to be operated by the response of the called subscriber to include current from said source in the line of the calling subscriber in a predetermined direction, an electromagnet in circuit with the calling-subscriber's line at the substation adapted to be energized upon the response of the called subscriber and mechanism controlled by said electromagnet adapted, upon its energization by a flow of current in said predetermined direction and then only, to collect a deposited coin.

15 18. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, a central source of current, apparatus at the central office adapted to be operated by the response of the called subscriber to include current from said source in the line of the calling subscriber in a predetermined direction, an electromagnet in circuit with the calling-subscriber's line at the substation adapted to be energized upon the response of the called subscriber, and mechanism controlled by said electromagnet adapted, upon its energization by a flow of current in said predetermined direction and then only, to collect a deposited coin.

30 19. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, a central source of current, apparatus at the central office adapted to be operated by the response of the called subscriber to include current from said source in the line of the calling subscriber in a predetermined direction, and apparatus associated with said pay-station device adapted to collect a deposited coin responsive only to a flow of current over said line in said predetermined direction.

35 20. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet in circuit with the calling-subscriber's line at the substation adapted to be energized upon the response of the called subscriber, mechanism controlled by said electromagnet adapted, upon its energization by a flow of current in said predetermined direction and then only, to collect a deposited coin.

65 21. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, a central source of current, apparatus at the central office adapted to be operated by the response of the called subscriber to include current from said source in the line of the calling subscriber in a predetermined direction, an electromagnet in circuit with the calling-subscriber's line at the substation adapted to be energized upon the response of the called subscriber, and mechanism controlled by said electromagnet adapted, upon its energization by a flow of current in said predetermined direction and then only, to collect a deposited coin.

70 22. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, a push-button adapted, when depressed by the subscriber, to engage said coin and cause movement thereof, a circuit-changing spring associated with said device, mechanical means for transmitting the motion of said coin to said spring, switching apparatus adapted, in response to such motion of said spring, to cause the bell of the called subscriber to ring, a central source of current, apparatus at the central office adapted to be operated by the response of the called subscriber to include current from said source in the line of the calling subscriber in a predetermined direction, an electromagnet in circuit with the calling-subscriber's line at the substation adapted to be energized upon the response of the called subscriber, and mechanism controlled by said electromagnet adapted, upon its energization by a flow of current in said predetermined direction and then only, to collect a deposited coin.

75 23. In an automatic telephone-exchange system, the combination with a calling-subscriber's line and a called-subscriber's line switched to electrical connection at the central office, of a pay-station device associated with the line of the calling subscriber at the substation, adapted to receive a deposited coin, switching mechanism associated with said device, ringing mechanism under control of the subscriber adapted to effect a movement of said coin to operate said switching mechanism, means adapted, in response to the operation of said mechanism, to cause the bell of the called subscriber to ring, an electromagnet in circuit with the calling-subscriber's line at the substation adapted to be energized upon the response of the called subscriber, mechanism controlled by said electromagnet adapted, upon its energization by a flow of current in said predetermined direction and then only, to collect a deposited coin.

a flow of current in a predetermined direction and then only, to collect a deposited coin, and a relay at the central office associated with the called-subscriber's line adapted to be operated by the response of the called subscriber to energize said electromagnet by causing a flow of current over the calling-subscriber's line in said predetermined direction.

In witness whereof I hereunto subscribe my name this 1st day of April, A. D. 1905.

ALFRED H. DYSON.
